VOTING MACHINE

Alvin N. Gustavson, Jamestown, N. Y., assignor
to Automatic Voting Machine Corporation,
Jamestown, N. Y., a corporation of Delaware

Application December 26, 1939, Serial No. 310,896

1 Claim. (Cl. 235—51)

This invention relates to an improvement in voting machines and particularly to interlocking mechanisms therefor.

The arrangement of controls, interlocks, etc. 5 in a voting machine for a general election is quite different from that for a primary election. In certain election districts where it may be found desirable to simultaneously hold a general and primary election it therefore becomes necessary, 10 in a machine to which the present invention is applicable, to add many auxiliary parts. The installation and set up of these parts for the purpose of adapting the machine to such a combination of voting involves considerable time and expense. 15

Voting machines of the type under consideration are made in several sizes for the purpose of adapting them to various communities or districts. Before a voting machine is installed for 20 use in a given election district, the size of the community, number of voters, and the possible variance in the number of voters over a period of years is ascertained in order that a machine of proper capacity may be provided. These machines are generally arranged with seven or more 25 horizontal or party rows of candidate indicators. The number of indicators in each row may range from thirty to sixty, depending on the size of the machine.

To illustrate one application of use of the invention, it is contemplated to utilize the three uppermost horizontal or party rows of candidate indicators for general election purposes and the remaining four or more rows for primary election 30 purposes. Each voting machine includes a main interlocking mechanism that may be connected with the three uppermost rows of candidate indicators through interlocking straps conventional to machines of this type. The remaining rows of candidate indicators are connected 35 through a different type of strap with a second interlocking mechanism. By providing two interlocking mechanisms, one of which is connected with certain rows of candidate indicators and the other with certain other rows of candidate indicators, the process of setting up a voting machine for a combined general and primary election involves no parts in addition to those commonly used in two separate voting machines for 40 the two types of elections. As will be more fully understood from the specification, means is provided by which a number of rows of candidate indicators in the so called general election group may be increased or decreased, as may be found 45 necessary.

The objects and advantages of the present invention, therefore, lie in the provision of a structure that adapts a voting machine for either primary or general elections or a simultaneous combination of these elections, together with the simplification of setting up a voting machine for 5 these purposes.

Other objects and advantages will be more fully understood from a consideration of the following specification taken in conjunction with 10 the accompanying drawing; and in which:

Figure 1 is a rear elevation of a voting machine interlocking mechanism embodying one form of the invention, parts being broken away to disclose certain of the structural details; 15

Figure 2 is a vertical sectional view, taken substantially on the line 2—2 of Figure 1, showing the relative position of two interlocks as well as the interlocking straps therefor;

Figure 3 is a side elevational view of a portion 20 of one type of interlocking strap;

Figure 4 is a side elevational view of a portion 25 of another type of interlocking strap; and

Figure 5 is a side elevational view of an auxiliary interlocking strap.

Reference is now had to the drawing wherein the numeral 10 is employed to indicate that portion of a voting machine known as an interlocking mechanism and by means of which manipulation of interlocking straps that are connected 30 with voter manipulated candidate indicators may be controlled. In the present modification of the invention the mechanism 10 comprises two interlocks 11 and 12. Suitable interlocking straps 13 project into the interlock 11 and in turn are 35 connected with the three topmost horizontal rows of candidate indicators on the face of a machine. The general structure of the interlock 11, interlocking straps 13, and connection with the candidate indicators is clearly illustrated in my Patent 40 #2,110,297 and the patent to Frank Keiper #1,031,184. The interlock 11 extends substantially the full width of the machine and may be supported for endwise movement or rigidly secured to the member 14 in any conventional 45 manner, as by screws 15. For a clearer understanding of the invention, it is assumed that the voting machine to which the present structure is applied comprises nine horizontal rows of candidate indicators of thirty indicators in a row. 50 The indicators of the three topmost rows are connected through straps 13 with the interlock 11. It will be noted, however, in the drawing that there are four interlocking straps 13 connected with the interlock 11. The endmost strap 55

13A in each group of four is required on all voting machines and serves to control use of a paper ballot write-in for candidates not listed. Thus viewing the interlock 11 in Figure 1, there 5 are groups of four interlocking straps spaced by four rollers. There will be thirty such groups of straps connected with this interlock, since it will be recalled the voting machine illustrated is arranged with thirty indicators per party row.

10 The interlock 12 is of slightly less height than interlock 11 but in all other respects is identical thereto. This interlock is joined in any suitable manner to interlock 11 and extends substantially the full width of the machine. Projecting into 15 this interlock are straps 14. These straps are somewhat different from the straps 13 and each includes a downwardly projecting portion 16 in which is an aperture 17 that receives the resetting bar 18. Projecting laterally downwardly 20 from adjacent the portion 16 is an arm 19 that terminates in a vertical portion 21 having the identical end structure of the interlocking strap 13. Both types of interlocking straps 13 and 14 are fitted with lugs 22, the purpose of which will 25 hereinafter be more fully set forth. The straps 14 connect the interlock 12 with the candidate indicators of the remaining horizontal rows on the machine.

From the description thus far it is evident 30 that as one views the interlocking mechanism 10 in Figure 1 of the drawing there will first be a group of four interlocking straps 13 and 13A projecting into interlock 11 and next a group of six interlocking straps 14 projecting into interlock 35 12 and this alternate arrangement of four and six straps extends throughout the length of the mechanism.

In a general election with candidates of different parties up for election to the same office, 40 a vote can be cast for only one of the candidates. In Figure 1 of the drawing grouping pins 23 serve to position certain of the rollers 24 of the interlock 11 so that only one of the group of three straps 13 can be raised by manipulation of the 45 corresponding candidate indicator on the face of the machine. It is apparent that the same measure of control over the operation of the candidate indicators in the group set aside for a general election may be had as in a voting machine set up only for a general election, rather 50 than the combination of a general and primary election. In the event that there are only two parties involved in a general election, it will be readily understood that the last interlocking strap 55 in each group of three in the interlock 11 may be isolated by a change in position of the grouping pin 23 or other suitable means. If it be-

comes necessary to increase the number of party rows of candidate indicators for a general election from three to four, that is, usurp one of the rows of indicators set aside for primary voting, auxiliary interlocking straps 26 may be utilized. 5 These straps, as shown in Figure 5 of the drawing, are attachable to the lugs 22 of straps 14. The offset portion 27 of these straps causes the enlarged blocks 28 to project into the interlock 11. Thus, in the present illustration thirty auxiliary straps 26 may be connected with thirty of the straps 14, and one of the rows of candidate indicators for use in primary elections will thus revert to use for general election purposes.

The purpose of utilizing the interlock 12 for a 15 primary election is to facilitate the addition of one or more auxiliary interlocks. The set up and voting in primary elections being more complicated, it is frequently necessary to provide auxiliary control beyond that of the interlock 12. 20 A properly contoured auxiliary interlocking strap can be readily attached to lug 22 of strap 14 and project into a suitable auxiliary interlock that is attachable to interlock 12 in one of several ways such, for example, as indicated in my Pat- 25 ents #1,948,661, and #2,110,297.

From the foregoing it is apparent that through the use of two or more types of interlocking straps and two or more interlocking mechanisms, 30 it is possible to combine in one voting machine a set up enabling the use of the machine for primary or general elections or both, and it will be understood by those skilled in the art that modifications of the present disclosure are contemplated insofar as such modifications are within 35 the spirit and scope of the invention as defined in the hereunto annexed claim.

Having thus set forth my invention what I 40 claim as new and for which I desire protection by Letters Patent is:

In a voting machine having a pair of interlocks in side by side arrangement, a series of interlock straps each comprising a body portion disposed directly above a first one of said interlocks and laterally offset with respect to a second one of said interlocks, certain of said straps reaching directly down into said first one of said interlocks, others of said straps each having a laterally inclined arm rigid with said body portion and reaching over to a position above the second of said interlocks, an enlarged end on said arm projecting into the second of said interlocks, and a resetting bar passing through aligned apertures in all of said straps and movable to operate 50 the same.

ALVIN N. GUSTAVSON.
